UNITED STATES PATENT OFFICE.

GEORGE W. MONTGOMERY, OF DES MOINES, IOWA.

IRONING BOARD AND CABINET.

Application filed July 27, 1921. Serial No. 487,964.

To all whom it may concern:

Be it known that I, GEORGE W. MONTGOMERY, a citizen of the United States, residing at Des Moines, in the county of Polk and State of Iowa, have invented certain new and useful Improvements in Ironing Boards and Cabinets, of which the following is a specification.

My invention relates to an ironing board which is enclosed in a cabinet fastened to the wall or placed on the floor in a room.

It is a rather difficult matter to find a proper place for storing away an ironing board when not in use and one object of the invention is to provide a permanent storing place for the ironing board which is situated in a room in a position most convenient for working, that is to say near a window or a light and the cabinet is made as small as possible for housing the ironing board so as not to constitute an obstruction in the room when the ironing board is not in use.

Another object of the invention is to provide a firmly supported ironing board that will neither move sideways or bend under the pressure of the iron when in use.

Other objects and advantages will be evident from the following description:

One embodiment of the invention is illustrated in the accompanying drawing:

Figure 1 represents the front elevation of the cabinet open with the ironing board folded within it;

Figure 2 is a longitudinal, central, sectional view of Figure 1.

The cabinet consists of a back panel 10 and a frame securely attached thereto having two sides 11 and top and bottom connecting pieces 12 and 13. A door 14 is hinged from the side of the cabinet and the structure is completely closed by this door when locked by lock 15.

Three spacing strips 16, 17 and 18 are shown running across the back panel of the cabinet at the center and top and bottom thereof. Below the spacing strip 18, is securely fastened at the back and sides of the cabinet, a beam 19 preferably of oak or some other hard wood so as to be able to withstand the strain put upon it by the ironing board when in use. The ironing board proper 20 which is of the usual rectangular shape with the free end 21 tapered, is secured to the cross beam 19 by means of stout hinges 22 which are placed in such position

that the ironing board 20 will lie prone against the spacing pieces 16, 17 and 18 when the ironing board is folded up in the cabinet, and will permit its swinging down to horizontal position when it is going to be used.

On the underside of the ironing board 20 are provided two or more trusses 23 which have a comparatively deep cross section and are tapered outwardly as at 24. These trusses run longitudinally of the ironing board and are hinged as at 26 to reinforcing strips 25 which are securely attached to the bottom of the ironing board 20 by means of screws or any other suitable means.

As will be seen in Figure 1 these trusses 23 fold toward the center of the ironing board 20 so as to lie flat upon the reinforcing strips and are secured in that position by means of a swivel latch 27. The ironing board 20 is also held in upright position by means of another swivel latch 28 near the top thereof.

At the bottom of the cabinet is placed a short board 30 which is provided with notches 31 to receive the trusses 23 and hold them rigid when the ironing board is in horizontal position. By this means it will be readily understood that when the ironing board is open for use, the supporting trusses 23 cannot be pushed inwardly which proves a considerable advantage over ordinary ironing boards where the supporting legs might easily be pushed or kicked away from under the board.

When the ironing board is not in use it is folded up as in Figure 1 and completely concealed as soon as the door 14 is closed and very little space will be taken up in a room and the ironing board will be entirely out of the way when not required for use.

The cabinet may be secured to a wall by any suitable means such as hooks or screws or else placed directly on the floor in which case suitable legs would have to be provided beneath it.

Having thus described the invention what is claimed as new is:

1. The combination of a cabinet and an ironing board, said ironing board fitting closely within said cabinet, a beam secured across the back of the cabinet and hinges connecting said beam and said ironing board, supporting members for the ironing board running longitudinally on the underside thereof, said supporting members being

hinged to the ironing board and adapted to lie flat thereon in one position and stand out perpendicularly thereto in another position, and guides for said supporting members at 5 the bottom of said cabinet adapted to secure the supporting members in said perpendicular position.

2. The combination of a cabinet and an ironing board, said ironing board fitting 10 closely within said cabinet, a beam secured across the back of the cabinet and hinges connecting said beam and said ironing board, supporting members for the ironing

board running longitudinally on the under side thereof, said supporting members being hinged to the ironing board and adapted to lie flat thereon in one position and stand out perpendicularly thereto in another position, guides for said supporting members at the bottom of said cabinet adapted to secure the 15 supporting members in said perpendicular position, and a swivel latch underneath the ironing board adapted to retain said supporting members when in folded position.

In testimony whereof I affix my signature. 20

GEORGE W. MONTGOMERY. [I. s.]
